UNITED STATES PATENT OFFICE.

ALLEN E. OSTRANDER, OF PATERSON NEW JERSEY, ASSIGNOR TO AMERICAN CAR & FOUNDRY COMPANY, OF ST. LOUIS, MISSOURI, A CORPORATION OF NEW JERSEY.

HOPPER-BOTTOM CAR.

No. 852,845.

Specification of Letters Patent.

Patented May 7, 1907.

Application filed December 28, 1906. Serial No. 349,879.

To all whom it may concern:

Be it known that I, ALLEN E. OSTRANDER, a citizen of the United States, residing at Paterson, New Jersey, have invented a certain new and useful Improvement in Hopper-Bottom Cars, of which the following is a full, clear, and exact description, such as will enable others skilled in the art to which it appertains to make and use the same, reference being had to the accompanying drawings, forming part of this specification, in which—

Figure 1 is a vertical longitudinal sectional view of one-half of a car constructed in accordance with my invention; Fig. 2 is a plan view of said car with a portion of the inclined floor plates broken away to show the construction of the underframe; Fig. 3 is a cross sectional view taken on the line 3—3 of Fig. 1; Fig. 4 is a cross sectional view taken on the line 4—4 of Fig. 1; Fig. 5 is a cross sectional view taken on the line 5—5 of Fig. 2; Fig. 6 is a cross sectional view showing a modified form of that part of my invention relating to side hopper sheets; and Figs. 7 and 8 show two different methods of connecting the bottom plates of the hoppers to the side sheets.

This invention relates to hopper bottom cars, and particularly to the car shown in United States Patent No. 816,070, to T. R. Brown, dated March 27, 1906.

The object of my invention is to simplify the construction of the car shown in the patent referred to so as to reduce the cost of manufacture and also to produce a stronger and more rigid construction.

Referring to the drawings which represent the preferred form of my invention, 1 designates the side walls of the car body which are made up of plates, and 2 designate angles that are connected to the upper and lower edges of said plates, thus forming a plate girder construction. The center sills of the car consist of rolled members 3, preferably channels, arranged with their flanges projecting inwardly although said channels may be arranged with their flanges projecting outwardly. Said center sill members are continuous from bolster to bolster and extend short distances beyond the bolsters. Fas-

ting to these extending portions of the center sills, as shown in Fig. 2, are draft sills 5 consisting of flanged members arranged with their flanges projecting in opposite directions to those of the center sills so that the webs of said center sill and draft sill members can be riveted together. Preferably, these draft sills are of channel shape but if desired, Z-shaped members could be used. The outer ends of the draft sills are connected to the end sill 5, and extending from said end sill to the bolster are sub-side sills 6 which are preferably Z-shaped members. The bolster consists of a continuous web plate 7 that is notched out to receive the center sills, and the opposite ends of said plate are connected to the side walls of the car by angles 8^a, said plate being strengthened by vertically disposed angles 8 and also having a bottom cover plate 9 secured to its lower edge. The Z-shaped sub-side sills 6 are connected to the bolster by brackets 10, the webs of said sills being secured to flanges on the brackets, as shown in Fig. 5. The main portions of the sub-side sills lie in lower horizontal planes than the lower edges of the side walls of the car but adjacent the bolster said sub-side sills are bent upwardly, as shown in Fig. 1, and the upper flanges thereof, which extend inwardly, are cut off so that the webs of said sills can extend between the ends of the web plate 7 and the side walls of the car to which the webs of said side sills are connected by rivets 11, as shown in Fig. 1. The angles 8^a which connect the web plate 7 of the bolster to the side walls of the car also secure said web plates to the webs of the sub-side sills and as these sills extend inwardly some distance beyond the bolster a very rigid construction is produced.

Diagonally extending braces 12, preferably channels, are connected to the brackets 10 and also to the center sills and end sills, as shown in Fig. 2, and the top cover plate 13 for the draft sills is reduced in width at its inner end and is connected to the top flanges of the center sills.

The inclined floor plates 14 which are connected to the side and end walls of the car are supported by the bolster web plate 7 and are connected to said plate in a novel manner. As shown in Fig. 1, the web plate 7 is provided at its upper edge with an integral flange 7^a which projects toward the end of

the car and is of the same inclination as the floor plates 14. Secured to the upper edge of the plate 7 and projecting oppositely to the flange 7^a is a pressed member which consists of a flange 15 that is secured to the plate 7, a web 15^a extending at right angles to the floor plates 14 and a flange 15^b to which the floor plates are riveted. This construction is very simple and forms a rigid support for the floor plates.

At the center of the car is a transversely extending cross ridge 16 and between said cross ridge and the inclined floor plates, the center sills are protected by pressed members 17 of inverted V-shape in cross section so as to deflect the load of the car into the hoppers arranged one each side of the centersills. The ends of said members 17 are provided with flanges 17^a which are connected to the cross ridge and to the inclined floor plates, and depending from the longitudinal edges of said members are flanges 17^b which in the preferred form of my invention shown in Fig. 3, are connected to the outer faces of the webs of the center sills. The inside sheets of the hopper are formed by plates 18 that are secured to the outer faces of the webs of the center sills. As previously stated, however, the center sills can be arranged with their flanges projecting outwardly, as shown in Fig. 6, and in such a construction the depending flanges 17^b on the members 17 will be made long enough to extend below the bottom flanges of the center sills. As shown in Fig. 6, the plates 18 which form the inside hopper sheets in this construction are secured to the lower edges of the flanges 17^b on said members and at the upper edges of the plates 18 are flanges 18^a which are preferably connected to the bottom flanges of the center sills. In this construction the members 17 are also preferably strengthened by continuous straps 19 secured to the webs of the center sills. The outside sheets of the hoppers consist of plates 20 that are secured to the side walls of the car, and the inclined bottom plates 21 of the hoppers which, in the construction herein shown, are continuations of the floor plates 14, are secured to the inside and outside sheets either by angles 22, as shown in Fig. 7, or they may rest on flanges 22^a formed integral with said sheets, as shown in Fig. 8.

The doors 23 for the hoppers are hinged at their upper edges to angles 24 on the cross ridge 16, and fastened to the inside and outside sheets of the hoppers are angles 25, the inwardly extending legs of which act as stops for the doors. The doors of each pair of hoppers are connected together by two angles 26 arranged to form a T and the door-operating mechanism is connected to an eye-bolt 27 arranged between said angles intermediate the doors. The door-operating mechanism herein shown consists of a manually-operated

shaft 28 provided with an arm 29 which is connected to the eye-bolt 27 by means of a link 30.

Having thus described my invention, what I claim as new and desire to secure by Letters Patent is:

1. A car comprising side walls, a body bolster, an end sill, and sub-side sills consisting of flanged members that extend inwardly from the end sill and are secured to the side walls intermediate the bolster and the transverse center of the car, the flanges of said sub-side sills being removed adjacent the bolster to permit the webs of said sills to lie between the ends of the bolster and the side walls of the car; substantially as described. 75
2. A car comprising side walls, a bolster, an end sill, and Z-shaped sub-side sills connected to the end sill and to the bolster, the sub-side sills being bent upwardly adjacent the bolster and having portions of their flanges removed to permit the webs thereof to be secured to the ends of the bolster; substantially as described. 80
3. A car comprising a bolster, side walls 90 extending over the ends of said bolster, an end sill, flanged sub-side sills secured to the end sill and to the side walls of the car intermediate the bolster and the transverse center of the car, one flange of each sub-side sill 95 being removed adjacent the bolster to permit the webs of said sills to lie between the side walls and the ends of the bolster, and brackets secured to the bolster and to the webs of said sub-side sills; substantially as described. 100
4. A car comprising a bolster, side walls extending over the ends of said bolster, an end sill, flanged sub-side sills secured to the end sill and to the side walls of the car intermediate the bolster and the transverse center of the car, one flange of each sub-side sill 105 being removed adjacent the bolster to permit the webs of said sills to lie between the side walls and the ends of the bolster, brackets secured to the bolster and to the webs of said sub-side sills, and diagonally extending braces secured to said brackets and to the end sill; substantially as described. 110
5. A car having inclined floor plates, a bolster consisting of a continuous web plate 115 provided at its upper edge with a flange that supports the floor plates and extends toward the end of the car, and a member secured to the web plate and to the inclined floor plates, said member having a portion which is disposed at right angles to the floor plates; substantially as described. 120
6. A car comprising center sills, a cross ridge, an inclined floor sloping downwardly from the end wall, and a cover for the center sills between the inclined floor and cross ridge consisting of a single metal plate of inverted V-shape in cross section; substantially as described. 125
7. A car comprising center sills, a central 130

cross ridge, hoppers on each side of the center sills, doors for said hoppers hinged at their upper edges to the cross ridge, a pair of transversely extending angles secured to the lower edges of the hopper doors and arranged to form a T, said angles being spread apart slightly at one point, a device interposed between the vertical legs of said angles at the point where they are spread apart, and a door-operating mechanism secured to said device; substantially as described.

3. A car comprising side walls, a bolster connected to the side walls, sub-side sills having inwardly projecting flanges which are cut away adjacent the bolster so that the

webs of said sub-side sills can lie between the side walls and the ends of said bolster and extend inwardly beyond the bolster and fastening devices connecting the sub-side sills to the side walls at a point intermediate the bolster and the transverse center of the car; substantially as described.

In testimony whereof I hereunto affix my signature in the presence of two witnesses, this 19th day of December, 1906.
